EXPANDING LAND ANCHOR

Frank W. Aiken, Moberly, Mo., assignor of one-half to John Earl Koester, Moberly, Mo.

Application February 10, 1941, Serial No. 378,257

4. Claims. (Cl. 189—92)

This invention relates to improvements in expanding land anchors and particularly to expanding land anchors that are reclaimable.

Heretofore anchors of this type have been difficult to reclaim and in many instances the cost of reclaiming is too high to justify the effort.

The principal object of the present invention is the provision of an expanding land anchor having retrieving means whereby the anchor is economically removed from its anchoring position in the earth.

Another object of the invention is the provision of an expanding land anchor having a body member with flukes pivoted thereto which are so positioned that the major pulling force exerted against the flukes will be transmitted directly to the body member and not to the pivot pins.

A further object of the invention is the provision of an expanding anchor having means whereby it is adapted to be carried and positioned by a jet pipe which directs a hydraulic jet to remove the earth from beneath the descending anchor.

Other objects are economy and durability of construction, ease and speed of setting and removing and adaptability for use under varying earth conditions and anchoring requirements.

With these as well as other objects which will appear during the course of the specification, in view, reference will be had to the drawings wherein:

Figure 1 is an elevation of an expanding land anchor partly broken away with the reclaiming cable omitted and with the flukes extended in dotted lines, embodying this invention.

Fig. 2 is a view similar to that shown in Fig. 1 with the anchor turned through a 90° angle.

Fig. 3 is a plan view of the anchor with the flukes shown extended in dotted lines and with the reclaiming cable omitted.

Fig. 4 is a vertical central section of the anchor taken on line IV—IV, of Fig. 2 with the rod and nut removed and the cable shown in this operative position and with the upper wings removed.

Fig. 5 is a modified form of the anchor showing but one pair of flukes and with the driving tube in position thereon.

Fig. 6 is a vertical central section taken on line VI—VI of Fig. 5.

Fig. 7 is a reduced vertical central section of the body member shown in Fig. 6 with the chains substituted for the cables.

Fig. 8 is an elevational view of an anchor

slightly modified to receive a jet pipe for positioning it in the earth.

Fig. 9 is a cross-sectional view taken on line IX—IX of Fig. 8.

Throughout the several views like reference characters designate similar parts and the numeral 12 indicates an elongated body member, pointed at its one end to form a pilot 14 for driving into the earth. This pilot is shown as rectangular in cross-sectional area, however they may be varied in design so long as the upper portion thereof is made of sufficient area to protect the more delicate portions of the anchor, as it is being driven into the earth.

15 The elongated body member is transversely grooved at its opposite sides at 16 to receive the pintel ears 18 of flukes or wings 20. Each fluke is provided with a pair of ears 18 which are spaced apart to straddle the body portion 22 of 20 the body member 12.

The ears 18 are provided with axially aligned holes 24 which are adapted to receive the end portions of pivot 26 which pass through opening 28 in the body portion 22. This opening 28 is 25 preferably made of a size suitable to present a drive fit for pivot 26 to secure the pivot against longitudinal movement therein. The ears 18 are formed as shown in Fig. 2 with offset portions to produce shoulders 30 which serve to contact 30 shoulders 32 formed in body member 12 to limit the pivotal opening movement of the respective flukes. Furthermore, the fluke is so bifurcated 35 to form the ears 18 that the end wall 34 of the slot contacts the body 22 to also limit the opening movement of the fluke. When so constructed and positioned, it is very apparent that the force exerted against the fluke when it is in the operative position will be exerted against the body member and that very little of the force will be 40 exerted against the pivot 26.

The flukes of the lower pair just described are disposed in opposed relation so that they will rest against the opposite sides of the body member when they are in the closed position such as 45 they take when being driven into the earth. When they are moved to the operating or holding position, as shown in dotted lines in Fig. 1, they are extended to present a maximum of resistance to the lifting of the anchor from its buried position.

Another pair of flukes similarly related are positioned intermediate the first described pair and the outer end of the body member. These flukes are mounted with their ears 18 positioned 55 in slots 36 and are disposed at right angles to the

flukes therebelow. It is quite apparent that other pairs of flukes of similar construction might be added to the anchor, thus increasing its resistance to an outwardly pulling force. While the four flukes shown, are disposed at 90° angles, relative to the adjacent flukes, yet it is apparent that the angled relation might be varied to any desired degree.

The upper end portion of body member 12 is downwardly tapered and is provided with a transverse rectangular opening 38 suitable for receiving a nut 40 which will be held against rotation therein. The upper portion of the body member is substantially planar at 42 and is provided with an upwardly extending cylindrical-shaped boss 44 through which is formed an opening 46 to receive a threaded rod or stake 48. This rod is adapted to be screw-threaded into nut 40 and serves for driving the anchor in certain instances and also for extending above the earth's surface to receive securing ropes or cables.

The boss 44 is adapted to receive a pipe 50, as shown in Fig. 5, for driving the anchor to the operative position. This driving means is utilized when the anchor is provided with flexible cable 52, as clearly shown in Fig. 4. After the anchor is driven the driving tube 50 is removed and the parts to be anchored are attached to the cable which extends above the earth's surface.

The cable 52, as clearly shown in Fig. 4, extends through opening 38 thence along the side of the body member 12 through opening 54 formed through the pilot 14 and thence back through opening 56 and upwardly along the side of body member 12. This cable is usually made of wire strands so that when it is thus threaded through the openings, as just described, it will resist slippage in the body member so that any desired amount of pull can be exerted on either end of the cable.

The end 58 of cable 52 serves as the guy cable to take the strain of the upward pulling force for anchoring of the member being held in position.

Cable 52 is adapted for use with the anchor forms shown in Figures 4, 5, 6, and 7, and the end portion 60 thereof serves as a reclaiming cable to upend the anchor so that it can be drawn from the earth with the flukes in the collapsed position. When it is desired to remove the anchor from the ground, cable end 58 is slackened and a pulling force is exerted on cable end 60 and since this portion of the cable is anchored to the pilot end of the body member, it will reverse the ends of the body member so that the anchor can be removed from the ground. When cable 52 is used with the anchor, rod 43 and nut 40 are left off, also, the upper pair of flukes 20 are removed to prevent interference with the cables and to also facilitate easier rotation of the body members on its transverse axis. In some instances only one of the flukes of the upper pair will be removed and the one opposite the cables will be left in position to increase the resistance due to the upward pull against cable 58. When the cable is threaded through the body member as shown in Figure 4 slippage of the cable in the body member will be resisted when the required force is applied to either portion 58 or 60 thereof.

The modified form, shown in Figs. 5 and 6 is a general purpose anchor with but two flukes oppositely disposed and mounted in a fore-shortened body member 62, transversely grooved at 64 to receive the fluke-hinge members, the pilot portion 66 being provided with transverse openings

68 and 70 and the upper portion of the body member being provided with a transverse opening 72. The upper portion 74 of the body member is substantially planar in form and is provided with an outwardly extending boss 76 over which pipe 50 is adapted to be fitted during the driving operation.

The cable 52 is threaded through the body member as just described, relative to Fig. 4, and functions in like manner.

The modified form, shown in Fig. 7, is substantially identical with that shown in Figs. 5 and 6, with the exception that a separate guy chain 78 connected by a clevis 80 to the body member 62 serves as the anchoring member while the chain 82 attached to the lower point of the body member serves as a retrieving member.

The modified form, shown in Figs. 8 and 9 is especially adapted for use in river-beds, soft soil, etc., and is adapted to be positioned by means of a jet pipe 84, having a collar 86 adjacent its lower end which is adapted to rest against an eye member 88 which projects from the side of the body member 62. This eye, as clearly shown in Fig. 9, has a pair of parallel free ends 90 which serve as pivots for the flukes 20.

It will be noted that the end of the jet pipe 84 extends slightly below the eye member 88 so that when the stream of water, or stream is forced through 84 it will clear away the soil or sand below the anchor member and as the jet pipe is moved downwardly the collar 86 resting against eye member 88 will also move the anchor downwardly. After it has attained the desired depth the jet pipe is removed and by placing a tension on the guy cable 90 the flukes 20 will be caused to open and the sand or soil will settle thereabove to form a definite anchorage of the flukes. With the cable 90 positioned as shown through the body member, it is apparent that the line of pull will be directly on the center line of the anchor.

A reclaiming cable 92 passes through the opening 94 formed transversely through the pilot of the body member and is clamped together by means of member 96. This reclaiming cable is operable to upset the anchor so that the pilot end of the anchor is turned upwardly during the removal from the operative position.

It will be noted that cable 92 is so attached to the anchor at its center line that the line of the cable during the retrieving operation will be in axial alignment with the body of the anchor, thus reducing the resistance of the anchor to the removal operation to a minimum. It is quite apparent that various arrangements of the guy cables and reclaiming cables might be had without departing from the general functioning of the device. Furthermore, the number and arrangement of the flukes relative to the body member may be varied so long as they function to close during the driving operation and to open as the guy cable exerts sufficient upward pull on the body member.

Having thus described my invention what is desired to be covered by Letters Patent is:

1. In an expanding land anchor an elongated body member having flukes pivoted adjacent its center portion for free limited hinged movement, and a cable secured intermediate its ends to said body member to extend from and engage each of its opposite ends.

2. In an expanding land anchor an elongated body member having an outwardly tapered pilot end portion, flukes pivoted for free limited pivotal movement to said body member during the full

operation of said anchor, a flexible cable secured to said pilot end portion of the body member and to the other end of said body member.

3. In an expanding land anchor an elongated body member, a plurality of flukes hingedly carried by said body member in spaced apart relation for free movement from a position substantially parallel with said body to a position transversely thereto, and a cable having a retrieving portion secured to the end portion of said body member below said flukes, and having an anchoring portion engaging the other end of said body member above said flukes.

4. A device of the character described, an elongated body member having its lower end portion tapered and provided at its two opposite sides with a fluke hinged at its lower extremity to the lower portion of said body member above said tapered end, and an operating cable secured intermediate its ends to said body member below said flukes having one portion thereof extending upwardly along said body member and another portion secured to said body member above said flukes.

FRANK W. AIKEN.
